UNITED STATES PATENT OFFICE.

ROLAND MORRILL, OF BENTON HARBOR, MICHIGAN.

DESIGN FOR A BODY FOR STOP-COCKS.

SPECIFICATION forming part of Design No. 34,797, dated July 16, 1901.

Application filed June 14, 1901. Serial No. 64,594. Term of patent 14 years.

To all whom it may concern:

Be it known that I, ROLAND MORRILL, a citizen of the United States, residing at Benton Harbor, in the county of Berrien and State 5 of Michigan, have invented and produced a new and original Design for a Body for Stop-Cocks, shown in the accompanying drawings, which are made a part of this specification, and in which—

10 Figure 1 is a perspective view of the body of a stop-cock of the new design. Figs. 2, 3, and 4 are elevations thereof viewed from different sides, and Fig. 5 is an end view thereof.

15 A stop-cock of the new design comprises a central portion A, having the general outline of a cross the arms of which are at right angles to each other. What may be termed the "longitudinal" arms terminate in bell-shaped

20 enlargements B and C, and within the latter is a tubular projection D. What may be termed the "transverse" arms have ribs E

equidistant from the center of the longitudinal arms, and one of said transverse arms has a cylindrical extension F, closed at its 25 outer end and having a polygonal flange G.

The essential feature of the new design is the cross-like configuration of the body and the cylindrical extension of one of the transverse arms of said cross, said extension being 30 closed at its outer end and provided with a polygonal flange.

Another feature of the design is the enlarged bell-shaped terminal of one of the longitudinal arms and the tubular extension 35 within said terminal.

What I claim as new is—

The design for the body of a stop-cock substantially as herein shown and described.

ROLAND MORRILL.
